UNITED STATES PATENT OFFICE

1,938,613

MACHINE FOR OPERATING UPON FRUITS
AND VEGETABLESJohn Herbert Stansbury, Fruitland, Md., assignor
of one-half to Ralph C. Dulany, Fruitland, Md.

Application July 29, 1929. Serial No. 381,809

17 Claims. (Cl. 146—55)

This invention relates to machines for operating upon small fruits and vegetables, for removing therefrom stems, caps and the like.

More particularly, the present invention is in the nature of an improvement upon and further development of the machine disclosed in my prior copending application, Serial No. 208,362, filed July 25, 1927.

While, as set forth in said prior application, 10 the invention is peculiarly applicable to the stemming and capping of strawberries, the principles employed are also well adapted for other purposes, as for example, the snipping of string beans.

15 Among the objects of the present invention are to provide an improved pinching mechanism, to provide improved means for driving and adjusting the conveyer belts, improved means for cleaning the pinching mechanism, and 20 generally to improve, simplify and commercialize the details of construction.

In order that the invention may be readily understood, reference is had to the accompanying drawings, forming part of this specification, 25 and in which:—

Figure 1 is an end elevation of the receiving end of my improved machine, parts being in section substantially on the line 1—1 of Figure 5;

30 Figure 2 is an end elevation of the delivery end of the machine, parts being omitted for the sake of clearness;

Figures 3 and 4 together constitute a side elevation of the complete machine, the central 35 portion being broken away, and some parts being omitted and other parts shown in an abnormal position for the sake of clearness of illustration;

Figure 5 is a partial plan view, showing the 40 receiving end of the machine, parts being omitted and parts being shown in an abnormal position, for the sake of clearness; and

Figure 6 is a fragmentary transverse section 45 on an enlarged scale, through the roller and apron constituting the pinching mechanism, and illustrating the manner in which such mechanism operates upon a strawberry.

Referring to the drawings in detail, the present machine comprises two end plates or castings 1 and 2, of the shape shown in Figures 1 and 2. These end plates are tied together at the bottom by tie rods 3, provided with nuts 3^a and surrounded by tubular spacing sleeves 4, as clearly shown in Figures 1 to 4. The end 55 plates are fastened together at the top by means

of a pair of angle irons 5 and 6, secured to each of the end plates by means of screws 7. Thus, a rigid frame is provided.

Power is supplied to the machine by means of a main shaft 8, on which is mounted for free 60 rotation a pair of rigidly connected driving sprockets 9 (see Figure 5). The outer end of the hub of these driving sprockets carries a clutch member 10, arranged to cooperate with a complementary clutch member 11, slidable on 65 a key 12, carried by the shaft 8, and adapted to be moved longitudinally of the shaft by means of a bifurcated lever (not shown) working in a groove 13, in a well known manner. The shaft 8 extends entirely through the ma- 70 chine from one end to the other, and is journaled in the end plates 1 and 2.

Adjacent and parallel with the shaft 8 is a second shaft 14, also extending through the ma- 75 chine and journaled in the end plates.

To the shafts 8 and 14, adjacent the driving end of the machine, are secured pinions 15 and 16, respectively, which pinions mesh with each other and with large gears 17 and 18, secured to the ends of shafts 19 and 20, journaled in the 80 end frames and extending through the machine.

Just inside the end plate 1, these shafts 19 and 20 carry worm gears 21 and 22, and with these worm gears mesh worms 23 and 24, secured to shafts 25 and 26, journaled in U- 85 shaped brackets 27 and 28. These brackets are themselves pivotally mounted about the shafts 19 and 20, and are supported and angularly adjusted by means of shafts 29 and 30, journaled at their lower ends in blocks 31 90 and 32, pivotally secured to the end plate 1, at 33 and 34. The upper ends of these shafts 29 and 30 are threaded and engaged in threaded blocks 35, 36, pivotally secured to the brackets 27 and 28. Each shaft 29 and 30 is provided 95 at its upper end with a hand wheel 37 or the like, by means of which it may be turned.

At the other end of the machine, as shown in Figure 2, similar swinging brackets 27' are provided, these brackets being similarly adjustable by means of shafts such as 29' journaled in a block 31' and provided with a hand wheel 37'. By reference to Figure 2, the method in which these brackets are pivotally mounted on the shafts 19 and 20 can be clearly seen, this 100 being accomplished by means of a divided journal bearing.

Rigidly secured to each of the shafts 25, 26, 25' and 26', at each end of the machine, is a flanged pulley 38. For reasons which will here- 110

inafter appear, the shafts at one end of the machine, as for example the shafts 25' and 26' are mounted in adjustable bearings. This is illustrated in Figures 2 and 3, in which each 5 end of each of these shafts is shown as journaled in a bearing block 39, slideable between the legs of a U-shaped bracket 40, having an end plate 41, and adjustable within this bracket by means of an adjusting screw 42, set into 10 the block 39 at one end, passing freely through an opening in the plate 41, and provided with a nut 43, bearing against the outside of such plate.

It may be explained here that in Figures 3, 4 and 5, the angularly adjustable brackets 27 15 and 28, carrying the shafts such as 25 and 26, are shown, for the sake of clearness, in a horizontal position, in order to illustrate the adjusting mechanism just described, and for other reasons. It will of course be understood that in 20 actual practice, these brackets occupy inclined or angular positions, as illustrated in Figures 1 and 2.

Passing around the pair of pulleys 38 at each 25 side of the machine, is an endless conveyer belt 44, designed to cooperate with the pinching mechanism hereinafter described, and it will now be obvious that the purpose of the adjustable bearings, such as shown at 39 in Figure 3, is to provide means for varying the tension on this 30 belt.

In order to support the belt and prevent it from sagging between the pulleys 38, I provide supporting or guiding means consisting of a pair of arms 45, secured to each bracket, such 35 as 27 and 28, and bridged by one or more cross pieces 46, to which are secured a pair of longitudinally extending strips or slats 47, (see particularly Figure 5. These supporting slats are omitted from Figures 3 and 4, in order to 40 avoid confusion).

Also secured to the shafts 8 and 14, just outside of the end plate 1, are sprockets 48 and 49, over which run sprocket chains 50 and 51, engaging another pair of sprockets 52 and 53, 45 secured to the ends of shafts 54 and 55. On these shafts 54 and 55 are mounted the pinching rollers 56, hereinafter more fully described.

Each shaft 54 and 55 is mounted in a series 50 of spaced bearings 57, secured to a supporting bar 58, this bar being itself adjustably attached to the angle iron 5 or 6, by means of a set screw or bolt 59, working through a slot 60 at each end of the bar. In order to further regulate and adjust the exact position of this bar 55 58, it carries at each end a pair of set screws 61, which bear against the angle iron and which are provided with lock nuts 62.

In order to prevent the supporting bar 58 and roller 56 from bending upwardly when in 60 operation, means are provided for holding it rigidly in exact alignment, as well as for adjusting it upwardly or downwardly, which means comprises a plurality of screws 63, having a threaded engagement with the angle iron 5 or 6, and bearing at their ends against the upper edge of the bar 58. These screws 63 have permanently fastened thereto at their upper ends wing nuts 64, by which they may be turned, and 65 they are also provided with lock nuts 65, by which they may be secured in adjusted position. It will be apparent that by loosening the bolts 59, the bar 58 may be adjusted vertically, as required.

75 Immediately beneath and adjacent the roller

56 is mounted a parallel shaft 66, as indicated in Figures 2, 3 and 4, and as shown in detail in Figure 6. This shaft 66 is supported at intervals throughout its length in bearing blocks 68 of the oilless type, engaging only the under side 80 of said shaft. The shaft is held against endwise movement by stops 67 adjacent each end thereof, (see Figures 3 and 4).

The bearing blocks 68 are supported at the upper edge of a bar or beam 69, itself adjustably secured at each end to the edge of the end plates 1 and 2, by means of bolts 73, working through slots 74, in the bar. The bar may be vertically adjusted, when the bolts 73 are loosened, by means of adjusting screws 70 threaded through lugs 71, on the end pieces and bearing against the lower edge of the bar or beam 69. The bolts 70 are provided with lock nuts 72, for securing them in adjusted position.

As it is quite a long span between the two end pieces of the machine, I have found it desirable to support the beam or bar 69 intermediate its ends, in order to prevent deflection thereof. This I accomplish by means of hooks or hangers 75, (see Fig. 2) having at their upper ends threaded shanks 76, passing freely through a cross piece 78, resting on the angle irons 5 and 6, the hooks or hangers being supported on this cross piece by means of nuts 77, (these hangers do not appear in Figures 3 and 4, because of the fact that the middle portion of the machine is broken away in these views).

Mounted on the shafts 19 and 20, between the end pieces 1 and 2, are rolls 79, having at each end, and at a plurality of points intermediate 110 their ends, radially extending flanges 80, as clearly shown in Figures 3 and 4.

Passing around these rolls 79 and the corresponding shaft 66, at each side of the machine, are endless flexible aprons 81, made in sections of such length as to fit between the said flanges 80 and guided by clips 81^a. These aprons 81 operate with the rollers 56 and constitute the other element of the pinching mechanism. The shaft 66 being arranged in such proximity to the roller 56 that the roller and apron form between themselves a bite. As shown in Figure 6, the flexible apron 81 is preferably provided with a corrugated outer surface, and may conveniently be made of rubber or the like, while the roller 56 is preferably fluted or provided with longitudinally extending teeth or ribs. These ribs or flutes cooperating with the corrugated surface of the apron as it passes over the shaft 66 produce a highly efficient pinching action, which is well adapted to engage and remove stems, caps and tips from berries and other vegetables.

As also shown in Figure 6, the conveyer belt 44 is disposed closely adjacent the upwardly 135 moving run of the apron 81, with the lower edge of the belt 44 slightly below the shaft 66, the belt 44 being inclined as shown. Thus, the belt and apron form a trough along which the berries, such as shown at x or other articles to be 140 operated upon, travel. The upward movement of the apron tends to lift or tumble the berries or other articles so as to present them properly to the pinching action of the bite between the roller and apron, and in this way, the stems, 145 caps, etc. are effectively removed.

By reference to Figures 1 and 2, it will be apparent that by turning the adjusting shafts such as 29 and 30, the angle of the conveyer belts 44 may be varied as desired, and also the distance 150

of such belts from the apron and roller may be adjusted. Furthermore, owing to the fact that there are separate adjusting shafts at each end of the machine, it is apparent that the two ends 5 of the conveyer belt may be independently adjusted, thus setting the belt at a distance from the apron which increases progressively from one end of the machine to the other, thus causing fruit of different sizes to be brought into 10 the bite of the roller and apron at different points in its travel along the belt.

At the opposite end of the machine from that shown in Figure 5, the shafts 8 and 14 carry sprockets 82, over which run chains 83, driving sprockets 84 on a pair of shafts 85 journalled in the end plates of the machine. These shafts 85 carry rotary brushes 86 of such size as to engage and sweep against the surface of the rollers 56 and apron 81 to clean the same. It will be 20 particularly noted, by reference to Figures 3, 4 and 5, that the bristles in these brushes 86 are set in spiral rows so that as the brushes turn, the bristles are brought into engagement with successive portions of the roller and apron 25 throughout their length.

In order to clean the brushes themselves, I preferably provide scraper plates 87. These may be secured by screws 89 and slots 88, (see Figure 5) to an angular supporting bar 90 having 30 upturned end portions 91 secured to the end plates 1 and 2 of the machine by bolts 92, working in slots 93, (see Figure 2). By virtue of these slots, it is obvious that the supporting bar 90 can be raised or lowered in order to properly 35 position the scrapers.

Referring to Figure 1, it will be seen that I preferably provide idler sprockets 94 engaging the sprocket chains 50 and 51, these sprockets being journalled in brackets 95 secured to the 40 end plate of the machine by means of bolts 97 working in slots 96, and it will be obvious that by loosening these bolts and moving the sprockets 94, the sprocket chains 50 and 51 may be tightened, as desired.

Similarly, as shown in Figure 2, I have provided idler sprockets 98 at the other end of the machine, engaging the chains 83, such sprockets being carried by brackets 99 secured to the end 50 plate of the machine, by bolts 100, working in slots 101, whereby they may be adjusted.

As shown in dotted lines in Figures 1 and 4, the fruit or vegetables to be operated upon are fed to the machine through chutes or spouts 102, these chutes having delivery nozzles so arranged as to deliver the articles into the troughs formed between the conveyer belts 44 and the aprons 81 at one end of the machine. The berries or other articles then are carried along 55 this trough by the travelling conveyer belt, and are brought into contact with the pinching mechanism, as they move along, and they are finally discharged from the delivery end of the machine, shown in Figure 2, a suitable trough or spout being arranged to cause them to fall clear of the mechanism. This spout, however, 60 is omitted from the drawings, for the sake of clearness.

The feeding mechanism of which the chutes 70 102 form a part may be of any suitable character but preferably is of the nature disclosed in my copending application filed of even date herewith.

The purpose of providing the machine with a double driving sprocket 9, as shown in Figure 5, will also be clear when considered in 75

connection with the above mentioned copending application. As shown in said application, it is proposed to drive a series of machines from a single source of power and the double sprocket is for the purpose of transmitting power from one machine to the next.

What I claim is:—

1. In a machine of the class described, an endless flexible apron, means for supporting and driving the same in a vertical plane with one run moving upwardly, a traveling support extending transversely of and adjacent said upwardly moving run, a pinching roller in co-operative relation with said apron, and means for rotating said roller.

2. In a machine of the class described, a horizontal shaft, an endless flexible apron passing over said shaft, a roller mounted above and parallel with said shaft, the surfaces of said apron and roller being disposed in pinching relation, and a traveling support extending longitudinally of and below said shaft and adjacent said apron.

3. In a machine of the class described, a pair of substantially horizontal shafts, mounted close together one above the other, a roller carried by said upper shaft, an endless flexible apron passing around said lower shaft, means for causing said apron to travel over said shaft, and means for causing articles to be operated upon to travel horizontally along the upwardly moving side of said apron adjacent said lower shaft.

4. In a machine of the class described, a horizontal roller, a shaft parallel with and below said roller, a driving roll, an endless flexible apron passing around said shaft and driving roll, said roller and apron being arranged closely adjacent each other so as to form a bite between them at the side, means for rotating said roller, and moving means for causing articles to be operated upon to travel along the bite of said roller and apron.

5. In a machine of the class described, a fluted roller and a transversely corrugated endless flexible apron mounted closely adjacent each other so as to form a bite between them, means for rotating said roller and causing said apron to travel, and means independent of said roller and apron for causing articles to be operated upon to move along said bite.

6. In a machine of the class described, the combination with pinching mechanism, including a horizontal roller, of conveying mechanism mounted at one side of and adjacent said roller and comprising a transversely inclined traveling belt extending longitudinally of said roller, and means for varying the angle of inclination of said belt.

7. In a machine of the class described, the combination with pinching mechanism, including a horizontal roller, of conveying mechanism mounted at one side of and adjacent said roller and comprising a transversely inclined traveling belt extending longitudinally of said roller, and independent adjusting means at each end of said belt for varying the angle of inclination thereof.

8. In a machine of the class described, the combination with pinching mechanism, including a horizontal roller, of conveying mechanism mounted at one side of and adjacent said roller and comprising a transversely inclined traveling belt extending longitudinally of said roller, and means for varying both the angle of in-

clination of said belt and its distance from said pinching mechanism. thereof and arranged to engage both said roller and apron to clean the same.

9. In a machine of the class described, the combination with pinching mechanism, including a horizontal roller, of conveying mechanism mounted at one side of and adjacent said roller and comprising a transversely inclined traveling belt extending longitudinally of said roller, pulleys over which said belt travels, swinging brackets in which said pulleys are supported and means for driving one of said pulleys.

14. In a machine of the class described, the combination with pinching mechanism including a substantially horizontal roller, of conveying mechanism mounted at one side of and adjacent said roller and comprising a transversely inclined flexible travelling belt extending longitudinally of said roller, and a rigid supporting strip substantially coextensive with and underlying the part of said belt adjacent said roller.

15. In a machine of the class described, a pair

10. In a machine of the class described, the combination with pinching mechanism, including a horizontal roller, of conveying mechanism mounted at one side of and adjacent said roller and comprising a transversely inclined traveling belt extending longitudinally of said roller, pulleys over which said belt travels, swinging brackets in which said pulleys are supported, means for adjusting said brackets on their pivots, and means for driving one of said pulleys.

15 of substantially horizontal rolling elements mounted with their surfaces close together and disposed one above the other so that the bite is at the side, means for driving said rolling elements, a conveyor belt extending longitudinally of and adjacent said bite, and serving to carry the berries along the same, and a supporting strip extending beneath and lengthwise of the belt and serving to hold the same up to said bite.

20 90 95

11. In a machine of the class described, the combination with pinching mechanism comprising a horizontal roller and an endless flexible apron arranged in cooperative relation therewith, of conveyer mechanism comprising a traveling belt extending longitudinally of said roller and mounted adjacent to and at an angle to said apron so as to constitute therewith a trough along which move the articles to be operated upon.

16. In a machine of the class described, pinching mechanism comprising a roller and means for rotating it, an endless flexible apron comprising a plurality of sections disposed side by side, means for supporting said apron closely adjacent said roller so as to form a bite between them, a compound driving pulley around which said apron passes, said pulley having a series of spaced radial guide flanges between which said apron sections fit, and means for causing

12. In a machine of the class described, pinching mechanism comprising an endless flexible apron, and a cooperating element, means for supporting and driving said apron so that one run moves upwardly toward said element, and a conveyer mounted adjacent said upwardly moving run and traveling in a direction at right angles to the movement of said apron.

35 articles to be operated upon to travel along said bite.

17. In a machine of the class described, and in combination, a plurality of adjacent units, each comprising a pair of rolling elements arranged one above the other in cooperative relation to form a bite between them, a transversely inclined conveyor extending longitudinally of said 40 units.

13. In a machine of the class described, the combination with pinching mechanism comprising a horizontal roller and an endless flexible apron arranged to form a bite between them, of a conveyor extending longitudinally of said roller at one side thereof, and a rotary brush extending longitudinally of said roller at the other side bite and forming a trough with said rolling elements, means for driving said elements and said conveyor, and a plurality of feed spouts, one for each unit, each spout being arranged to deliver into said trough the articles to be operated upon. 120

JOHN HERBERT STANSBURY.
